Canada LLP

(57) CLAIM

The ornamental design for a spring for vehicle suspension as
shown and described.

DESCRIPTION

FIG. 1 is a perspective view of a first embodiment of a spring
for vehicle suspension showing the design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a
spring for vehicle suspension;

FIG. 9 is a front view thereof;

FIG. 11 is a left side view thereof;

FIG. 12 is a right side view thereof;

FIG. 13 is a top view thereof;

FIG. 14 is a bottom view thereof;

FIG. 15 is a perspective view of a third embodiment of a
spring for vehicle suspension;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a perspective view of a fourth embodiment of a
spring for vehicle suspension;

FIG. 23 is a front view thereof;

FIG. 24 is a rear view thereof;

FIG. 25 is a left side view thereof;

FIG. 26 is a right side view thereof;

FIG. 27 is a top view thereof;

FIG. 28 is a bottom view thereof;

FIG. 29 is a perspective view of a fifth embodiment of a
spring for vehicle suspension;

FIG. 30 is a front view thereof;

(Continued)

FIG. 31 is a rear view thereof;
 FIG. 32 is a left side view thereof;
 FIG. 33 is a right side view thereof;
 FIG. 34 is a top view thereof; and,
 FIG. 35 is a bottom view thereof.

The broken lines shown in the drawings illustrate portions of the spring for vehicle suspension that do not form part of the design. The bold wavy lines do not form part of the design and are included to indicate boundaries of the design. Appearance of any portions of the spring for vehicle suspension between the parallel lines broken by a zigzag in the drawings form no part of the claimed design and indicate that the article is of indefinite length. The spring for vehicle suspension may be used as part of a suspension of a vehicle such as an automobile.
